BABY NURSING BOTTLE HOLDER

Norman R. Lykes, Maricopa County, Ariz.

Application July 21, 1958, Serial No. 749,772

2 Claims. (Cl. 248—106)

This invention concerns a baby nursing bottle holder.

One of the objects of the invention is to provide a nursing bottle holder which can be placed in the crib or bed occupied by the baby and which will stand erect and hold the bottle of milk or the like at any height desired and at any angle desired.

Another object of the invention is to provide a baby nursing bottle holder which is of simple rugged design and made of a minimum number of parts and which will hold the bottle as desired without tipping or interfering with the comfort and position of the baby.

Still another object is to provide a holder as above described which is easily and cheaply made and ruggedly constructed.

Other objects will appear hereinafter.

I attain the foregoing objects by means of the construction, parts and combination of parts illustrated in the accompanying drawings in which,

Figure 1 is a side elevational view of a baby bottle holder incorporating my improvements;

Figure 2 is a plan view thereof; and

Figure 3 is an end view thereof.

Similar numerals refer to similar parts in the several views.

The holder is characterized by the angular ridge pole 2. This is supported at the left end by two legs 3 and 4, respectively, which extend downwardly and diverge angularly from the raised end of the pole. The opposite end 5 of the pole 2 rests directly on the bed 6. This construction makes a 3 point support for the holder which is non-tipping and adapted to any irregularities of the bed or covers thereon.

The ridge pole 2 is preferably round and supports a clamp 8. This is made of 2 elements 9 and 10 held together by a bolt 12 having a wing nut 14 which tightens the rounded grooves 15 of the clamp on the pole. The head of the nut is also inserted through a loop 16 in a wire bottle holder 17. This bottle holder has a small ring 18 at the bottom and a larger ring 20 at the top, both being adapted to receive and hold a standard nursing bottle.

The loops are joined by a U shaped yoke 21 in the middle of which is the ring for loop 16 which is held by the head of bolt 12.

From the foregoing it will be seen that there is but one adjustment screw necessary. The bolt when tightened holds the bottle carrier and likewise clamps the

2

parts 9 and 10 on the pole 2. By shifting the carrier and clamp along the ridge pole variations in height may be made, and by turning the clamp on the ridge pole variations in the longitudinal angle at which the bottle is held may be made. By rotating the bottle holder, variations in the transverse angle at which the bottle is held may be made.

The legs 3 and 4 are preferably inserted into holes 7 and 7' drilled at downwardly diverging angles on the lower portion of the upper end of pole 2. The holes are spaced apart along pole 2 and are also drilled at angles relative to the length of pole 2 to hold legs 3 and 4 erect on the surface of bed 6 relative to the slant of pole 2. They are preferably held by friction fit in holes 7 and 7'. They may be withdrawn from holes 7 and 7' and bundled parallel with pole 2 when the device is not in use. This makes a very compact package and is easy to set up to working position as shown in the drawings.

It is to be noted the bottle is indicated in dotted lines and suggested movement of the bottle is indicated by the arrows 22.

I claim:

1. A nursing bottle holder for infants consisting of a slanting ridge pole support having a lower end adapted to rest on a surface to gain support, and holes in the upper end of said ridge pole to hold and direct two erect downwardly diverging supporting legs from the upper end of said pole; the lower ends of said legs being adapted to rest on said surface to gain support, a two piece clamp held together by a bolt extending through said clamp pieces, jaws formed on said clamp pieces adapted to clamp on said ridge pole support, and a nursing bottle holder consisting of two rings, adapted to receive and hold a nursing bottle, and a yoke connecting said rings having a loop at its center pivotally held on said clamp by the bolt on said clamp.

2. A nursing bottle holder for infants consisting of a slanting ridge pole support having a supporting foot portion at its lower end, and downwardly diverging legs extending from its upper end, a two jaw clamp adapted to clamp on said ridge pole at any desired position along its length; a threaded bolt, having a head, extending transversely through said jaws and a wing nut on the threaded end of said bolt adapted to clamp said jaws on said ridge pole support; and a nursing bottle holder composed of a large ring to hold a nursing bottle body and a smaller ring, to hold the neck of the nursing bottle, disposed in spaced relation with their axes alined and joined by a yoke having a centrally located loop secured under the head of said bolt, said ridge pole having two longitudinally spaced holes at its upper end to receive said diverging legs with a friction fit and hold said legs in an erect position relative to said slanting ridge pole.
